Inventor:

Henry M. Paine

UNITED STATES PATENT OFFICE.

HENRY M. PAINE, OF NEWARK, NEW JERSEY, ASSIGNOR TO BENNET OSBORN, OF SAME PLACE.

NOSE-PIECE FOR EYEGLASSES.

SPECIFICATION forming part of Letters Patent No. 247,681, dated September 27, 1881.

Application filed March 30, 1881. (No model.)

To all whom it may concern:

Be it known that I, HENRY M. PAINE, a citizen of the United States, residing at Newark, in the county of Essex and State of New Jersey, have invented a new and useful Improvement in Eyeglasses, of which the following is a specification.

The object of my invention is to substitute an elastic nose-clamp for the usual rigid device, and thus distribute the pressure over a larger portion of the nose than has hitherto been accomplished.

The nature of my invention consists in constructing the nose-clamp of round wire, wound spirally, or flattened wire, wound helically, as shown at *a a* in the accompanying drawing, making part of this specification.

To insure pliancy of the clamps *a a* their

coils should be well opened before being secured to the frame of the eyeglass.

I have not mentioned any method of attaching the spring-clamps to the frame, as different makers will devise their own modes; but I have found in practice that a very neat attachment can be made by brazing, using a solder that flows at a comparatively low temperature.

I claim as my invention and desire to secure by Letters Patent—

The spiral clamps *a a*, in combination with the frame of the eye-piece, substantially in the manner and for the purpose set forth.

HENRY M. PAINE.
